HEAT RADIATOR FOR FURNACES

Theodore W. Munford, Toledo, Ohio, assignor to
Surface Combustion Corporation, Toledo, Ohio,
a corporation of New York

Application March 1, 1937, Serial No. 128,372

3 Claims. (Cl. 263—42)

This invention relates to improvements in heat-radiating means for furnaces commonly employed for heating a pack of sheet steel supported on a base forming part of the furnace structure. In 5 furnaces of this type, it is desirable to concentrate the heating, during the heating up period of the steel, near the base of the furnace to compensate for the fact that the pack is supported on the furnace base, and thereafter to distribute the heat 10 more uniformly between the top and bottom of the pack. With that desirability in mind, it is the object of the invention to provide a fuel-fired radiator which shall be capable of operation to accomplish that result and which shall be 15 particularly well adapted for use in furnaces of the type mentioned. In some respects, the invention may be considered as an improvement on the firing system disclosed in patent to Hepburn 2,041,341 dated May 19, 1936.

20 Referring to the accompanying drawing wherein the preferred form of the invention is shown,— Fig. 1 is a vertical longitudinal section of a heating furnace embodying the present invention, the view being taken on line 1—1 of Fig. 2, and 25 Fig. 2 is a vertical cross-section on line 2—2 of Fig. 1.

In the drawing, 5 indicates the base of the furnace and 6 a hood which is removably seated thereon to form a heating chamber. The pack of 30 sheets to be heat-treated is indicated at W, in dotted lines, and is supported on a raised platform 7 forming part of furnace base.

The improved heat radiator is generally indicated at 8, the same being disposed along the 35 side wall of the hood and comprising at least three tubular legs 9, 10, and 11 which extend in a common direction from a header 12, the legs being shown as entering the hood through one and the same end wall thereof. Ordinarily there will be 40 two radiators along each of two opposite walls of the hood, the arrangement in this respect being similar to that disclosed in the said Hepburn patent.

The lower leg 9 of the radiator will ordinarily 45 be of greater cross-sectional area than either of the other two legs. Fluid fuel is delivered to the outer end of the lower leg 9 by a burner 13 which, for the purposes of this description, may 50 be considered as identical with, or of the same type as, the burner disclosed in the said Hepburn patent. Coupled to the outer end of the other two legs 10 and 11 are identical suction-producing devices 14 and 15. These devices are preferably 55 jet-operated exhausters of the same type as that disclosed in Fig. 8 of the said patent to Hepburn. The pipes for supplying operating fluid to the exhausters are indicated at 16, each pipe having a shut-off valve 17. At the outer end of each 60 ehauster is a manually adjustable damper 18.

The primary function of the exhausters is to pull combustion supporting air into the lower combustion leg 9. However, whether both or only one of the exhausters shall be turned on will depend on heat requirements. Thus when the pack is cold, the upper exhauster 15 may be turned off but with its damper 18 open to permit secondary air to flow into the tube 11 under the influence of the draft or suction produced in the header 12 by the other exhauster 14. The air thus reaching the header will, of course, accelerate combustion of the residual fuel in the gases coming from the primary combustion leg 9 and thus cause the leg 10 to become hotter near the header 15 than it ordinarily would. The heat of the fuel will, therefore, be concentrated near the bottom of the pack as is desirable when the pack is cold. Later on in the heating period, the exhauster 15 will also be turned on whereby to draw heating 20 gases into the tube 11 with resultant more uniform application of heat to the pack. It may sometimes be desirable to shut off the lower exhauster 14 while leaving the upper exhauster 15 turned on with the end in view of pulling all of 25 the heating gases through the upper leg. In such event the damper 18 associated with the lower exhauster may be closed or left open as heating requirements demand.

Since both exhausters are individually regulable and are each provided with a damper and the amount of fuel supplied by the burner 13 is also subject to regulation, it will be readily appreciated that the production of heat and its 35 distribution may be controlled to a nicety.

What I claim is:

1. The combination with the heating chamber having a base on which the material to be heated is supported, of means for producing the heat in the chamber comprising a fuel fired radiator therein, said radiator having at least three horizontally extending heat radiating tubes disposed one above the other in spaced relation and a header connecting the tubes at one end, the other end of the tubes extending out of the chamber, a burner for supplying fuel to the outer end of the lowermost of said tubes, and individually regulable exhausters coupled to the outer end of the other tubes.

2. In the combination specified in claim 1, the lowermost of the said tubes being in relatively close proximity to the said base and being of greater diameter than the next adjacent tube.

3. The combination specified in claim 1 characterized by means for closing the flow passage through at least one of said exhausters.

THEODORE W. MUNFORD. 60
